UNITED STATES PATENT OFFICE.

WILLIAM B. LICHTIG, OF NEW YORK, N. Y.

WASHBOARD.

No. 843,469.

Specification of Letters Patent.

Patented Feb. 5, 1907.

Application filed August 11, 1906. Serial No. 330,208.

To all whom it may concern:

Be it known that I, WILLIAM B. LICHTIG, a citizen of the United States, residing in New York, borough of Manhattan, county and 5 State of New York, have invented certain new and useful Improvements in Washboards, of which the following is a specification.

This invention relates to washboards. 10 The object of the invention is to provide a washboard embodying a rubbing device which exerts an efficacious cleaning action on the articles to be washed and by which the holding of such articles in the hands in order 15 to rub them on the board and the consequent soaking of and injury to the hands is obviated.

With these ends in view the invention consists in the novel features and combinations 20 of parts to be hereinafter described and claimed.

In the accompanying drawings, in which the same reference characters denote the same or corresponding parts throughout the 25 several views, Figure 1 is a front elevation of a washboard constructed in accordance with the invention. Fig. 2 is a similar view, but showing the rubber-carrying frame swung back from the rubbing-surface of the board. Fig. 3 is an enlarged horizontal section on line 3-3, Fig. 1.

In the drawings, 1 indicates the washboard proper, which is of the usual construction, having a rubbing-surface 1¹, covered with 35 corrugated sheet metal. A rectangular frame 2 is hinged laterally to said board at one side of the same in such a manner as to extend over the rubbing-surface 1¹ or to be swung back away from the front of the same, as 40 shown in Fig. 2.

3 denotes the hinges by which the frame 2 is applied to the washboard. Said frame embodies side pieces 4, which are provided at their inner faces with longitudinal grooves 5, 45 as shown. These grooves are preferably provided with a sheet-metal lining 6. Cross-strips 7 are suitably secured at their ends in said grooves and constitute the upper and lower members of the frame 2.

50 The grooved side pieces 3 of the frame 2 serve as guides for a rubbing device 8. This device is illustrated as consisting of a rectangular block having side flanges 9, which enter the grooves 5. The grooves are made of

greater width than the thickness of the rubbing-block 8, so as to yield sufficiently to the thickness of the clothes placed between the board and the block during the rubbing operation. By this means the rubber 8 is freely guided in upward and downward direction 60 in the frame 2. The rubber 8 is provided at its inner surface with a metallic corrugated rubbing-surface 10, cooperating with and similar to that of the washboard proper. A handle 11 is applied to the opposite face of 65 the rubbing block.

The operation of the device is as follows: The frame 2 being swung back from the rubbing-surface of the washboard, as shown in Fig. 2, the article to be washed is placed on 70 said-surface. The frame is then swung over said surface, as shown in Fig. 1, so that the rubber 8 lies on the article. Said rubber is then reciprocated in upward and downward direction while gradually pulling the article 75 in upward direction its handle 11 being grasped by one hand or both. Such reciprocation causes an efficacious and successive rubbing of the entire article between the corrugated rubbing-surfaces of the board and 80 the rubber. When the article is sufficiently clean, it is removed through the upper open portion of the frame, after which the next article is placed in position by opening the frame, lifted from the washtub onto the wash- 85 board, after which the guide-frame, with the rubbing-block, is placed thereon, the article being then rubbed and removed through the upper part of the frame, and so on. The cross-strips 7 limit the movement of the rub- 90 ber upwardly and downwardly.

A great deal of pressure may be exerted on the article to be washed by means of the rubbing-block, and this, together with the cooperative action of the two rubbing-surfaces, 95 produces a thorough washing of the article with a minimum expenditure of energy and without necessitating the long-continued soaking of the hands in the suds.

Having thus described my invention, I now claim as new and desire to secure by Letters Patent . . .

The combination, with a washboard having a corrugated rubbing-surface, of a guide-frame hinged to one side of said board and 105 embodying grooved side pieces and transverse end pieces, a rubbing-block also provided with a corrugated rubbing-surface and

guided in upward and downward direction in
the grooves of the guide-frame, and a handle
applied to said block, the grooves in said side
pieces of the guide-frame being of greater
5 width than the thickness of the block, so as
to provide for the varying thickness of the
articles to be washed.

In testimony that I claim the foregoing as
my invention I have signed my name in pres-
ence of two subscribing witnesses.

WILLIAM B. LICHTIG.
